PIVOTAL TRAY

Samuel M. Seltzer, 85 Athens Road,
Short Hills, N.J. 07078

Filed Oct. 24, 1972, Ser. No. 299,655

Term of patent 14 years

Int. Cl. D8—99, D15—99
U.S. Cl. D55—1 H

FIG.1

FIG.2

FIG.3

FIG. 4

FIG. 5

FIG. 6

FIG. 7

FIG. 8

FIG. 1 is a front, top and left side perspective view of a pivotal tray, showing my new design;

FIG. 2 is a top plan view;

FIG. 3 is a front elevational view;

FIG. 4 is a left side elevational view;

FIG. 5 is a right side elevational view;

FIG. 6 is a bottom plan view;

FIG. 7 is a sectional view along line 7-7 of FIG. 2; and

FIG. 8 is a rear elevational view.

I claim:

The ornamental design for a pivotal tray, substantially as shown.
